J. E. CHAMBERS,
COMBINED GAS STOVE AND FIRELESS COOKER.
APPLICATION FILED JULY 13, 1916.

1,321,189.

Patented Nov. 11, 1919.

UNITED STATES PATENT OFFICE.

JOHN E. CHAMBERS, OF SHELBYVILLE, INDIANA, ASSIGNOR TO CHAMBERS MANUFACTURING COMPANY, OF SHELBYVILLE, INDIANA, A CORPORATION OF INDIANA.

COMBINED GAS-STOVE AND FIRELESS COOKER.

1,321,189.

Specification of Letters Patent.

Patented Nov. 11, 1919.

Application filed July 13, 1916. Serial No. 109,147.

To all whom it may concern:

Be it known that I, JOHN E. CHAMBERS, a citizen of the United States, residing at Shelbyville, in the county of Shelby and State 5 of Indiana, have invented certain new and useful Improvements in Combined Gas-Stoves and Fireless Cookers, of which the following is a specification, reference being had therein to the accompanying drawing.

10 This invention relates to cooking apparatus and more particularly to that type of apparatus known as combined gas stove and fireless cooker, embodying means whereby the apparatus may, at will, be either utilized 15 as a gas stove or a fireless cooker, in which latter event the initial heat is obtained by the gas flame, and the cooking operation continued to completion, after shutting off the flame, through the medium of the stored up 20 heat previously generated or derived from the use of a flame.

It is one of the primary objects of the present invention to provide a novel construction of oven in an apparatus or stove 25 of the fireless cooker type, said oven having associated therewith means whereby receptacles containing material to be cooked may be placed within the oven, side by side, and the material in the respective receptacles 30 simultaneously subjected, the one to boiling, and the other to roasting or baking treatments.

A further object of the invention resides in the provision of novel construction 35 and arrangement of burners in operative association with the oven, with means whereby the burners in the respective sections of the oven may be simultaneously lighted or extinguished as desired.

40 More particularly the invention includes a novel construction of fireless cooker embodying a normally inclosed oven with a plurality of gas burners or the like normally covered by heat radiating plates, which said 45 plates are removable to expose one or more of the burners, to the exclusion of the others, to the interior of the oven whereby the contained material may be subjected to the direct flame of the exposed burners, and means 50 whereby the ignition of the plurality of burners is simultaneously effected.

Other improvements and novel details in the construction and arrangement of the various parts will be appreciated from the 55 description to follow, which, for a clear un-

derstanding of the invention, is to be considered in connection with the accompanying drawings, forming a part hereof, and wherein is disclosed for the purpose of illustration a convenient and satisfactory embodiment of the invention, though it is to be understood in this connection that various details in such construction and arrangement of parts may be varied and still be within the spirit and contemplation of the 65 invention.

In the drawings:

Figure 1 is a perspective view of a stove having my improvements applied thereto, the oven doors being open whereby to expose the 70 interior construction.

Fig. 2 is a horizontal section of the lower portion of the stove.

Fig. 3 is a vertical sectional view substantially on the line 3—3 of Fig. 2. 75

With more particular reference to the drawings, wherein like reference numerals refer to corresponding parts throughout the several views, 1 are suitable standards or feet adapted to support the stove or range proper. 80 2 is a suitable top of any desired construction and having inserted therein gas burners 3 of any approved type, the latter being adapted to receive their supply of gas through the medium of a conduit 4 having 85 valves 5 for controlling the supply of gas into the respective burners. The conduit 4 connects with a vertically disposed section 6 which latter in turn connects with the main supply pipe 7 leading from any suitable 90 source.

The structure above described may be said to represent the upper portion of an ordinary type of gas range, but it is desirable to couple up with a range of this character an oven construction of novel design with operatively associated burners to the end that the oven section may be utilized as customary in ordinary gas ranges or as a fireless cooker. The oven, generally 95 speaking, preferably has walls comprising inner and outer sections of suitable material such as sheet metal with the space between the inner and outer wall sections filled with a suitable packing of 100 fire proof material of construction to retain the heat within the cooking compartments, after the fashion of fireless cooker constructions. Likewise the door 8 is similarly constructed of inner and outer walls with suit- 110

able filling material interposed between the walls so that the door when in closed position constitutes in effect a continuation of the walls of a cooking chamber. The parts 5 of the oven are so constructed and arranged as to afford a cooking chamber of increased proportions, it being desirable in the present instance to provide sufficient area within the oven for simultaneously boiling and roasting 10 or baking operations. In this connection the receptacles adapted to contain the materials for the above treatments are conveniently arranged side by side within the oven whereby they may be disposed, the one 15 above one burner and the other above another burner, the latter to be presently described.

The walls of the oven are normally substantially closed throughout, the bottom 20 wall 2^a being provided with a suitable valve or damper controlled draft opening, not shown, and adapted to support thereon a suitable bottom plate 9 having an annular flange 10 resting upon the bottom wall 2^a. The plate 9 is perforated whereby to distribute air taken into the apparatus through 25 the draft opening. A baffle plate or partition 11 forms in effect the bottom of the oven and is spaced upwardly from the bottom wall 2^a, previously referred to, a substantial distance whereby to provide, together with the side walls of the stove, a substantially closed burner chamber 12. The baffle plate is supported upon the perforated plate 9 by downwardly extending 30 peripheral supports 13. The baffle plate or partition 11 is provided therein with a plurality of annular openings 14, two being illustrated in the drawings, one at each side 35 of the center of the baffle plate and the walls of the plate 11 which surround said opening 14 being provided with suitable flanges or supporting lips 15 adapted to receive a detachable plate 16. The plates 16 have in 40 the upper surface thereof suitable engaging parts 17 adapted for the reception of a suitable lifter or other tool whereby the plates 16 may be removed somewhat after the fashion of the ordinary stove lid. Likewise 45 the baffle or partition plate 11 may be provided with a suitable engaging recess 18 for the reception of a similar tool to the end that the baffle plate may be removed as desired. The removable baffle plate together 50 with the removable lid or plate section 16 are essentially heat reservoirs or heat radiating plates.

It is desirable to provide in the burner 60 chamber 12 a plurality of burners, there being preferably a burner below each removable lid section 16 and said burners being preferably constructed as follows:

The burners are preferably of star shape comprising a hollow body portion 19 and a 65 plurality of tubular wings or projections 20

having in the upper surface of the latter separated gas outlet ports 21. One of the projections 20 of one burner is placed in direct communication with a coöperating projection 20 of the other burner through 70 the medium of a tubular conduit 22 having therein a series of separated closely associated outlets 23 to the end that assuming that a supply of gas is imparted to one burner the flame will be carried from the said burner along the conduit 22 thereby igniting the gas in the coöperating burner. In this way, assuming that gas is simultaneously fed to both burners, the latter will be simultaneously ignited. The burners receive their 75 supply of gas from suitable conduit 24 projecting through the bottom wall 2^a of the apparatus and communicating with the gas supply conduit 7 in any desired manner, the supply of gas being controlled through the 80 medium of a hand operated valve 25. A suitable vent for the oven is indicated at 26, the same being adapted to be controlled by a damper or closure, the closure actuating means being operatively associated with the 85 handle of the valve 25 to the end that as the gas supply valve 25 is moved to open position, the vent valve will be simultaneously opened, whereas if the valve 25 is moved to a closed position, the vent valve will be 90 simultaneously closed. This construction of 95 vent valve actuating means and its coöperative relationship with the gas supply valve is not deemed necessary to show herein in that the same may be of any desired construction 100 for the purpose, such for instance as illustrated in my copending application Serial No. 618,047 filed March 21, 1911, entitled Combined gas stove and fireless cooker. The operation of the present construction 105 may be reviewed as follows:

It has been seen that the oven is preferably somewhat wider than any ordinary standard construction of the character under consideration with the result that the same 110 will accommodate two or more utensils side by side. Assuming that it is desired to boil the material in the utensil in one side of the oven, a lid is removed and the kettle or other receptacle is placed directly over the flame 115 of the burner below said lid. If it is desired to roast or bake, the lid remains in place at the base of the oven so that the heat will be distributed. In this manner boiling may be accomplished on one side of the oven and 120 roasting or baking on the other. The burner herein provided is of peculiar advantage in connection with the type of oven illustrated, for the reason that it is found necessary to heat the bottom plate of the 125 oven thoroughly in order that the same may remain heated after a considerable length of time. Should two separate burners be employed, and but one side of the oven heated at a time, the relative cold bottom plate at 130

the other side of the oven would tend to withdraw the heat from the heated side and materially limit the heat retention of the latter. Where a plurality of burners are employed, however, as illustrated, it is important that they be operated simultaneously, or with a single valve and lighted, since the ordinary user could not be depended upon to light both burners were the 5 burners independent. It has been appreciated that so soon as one of the burners are lighted in the construction embodied herein, the connecting tube or bridge of gas ports insures the carrying of the flame from one 10 burner to another.

What I claim is:

1. In a combined fireless cooker and gas range, the combination of a substantially closed oven structure surrounded by walls of 20 non-conducting material, a plurality of spaced radiating plates adjacent the base of the oven, a gas burner substantially centrally disposed beneath each radiating plate and extending throughout a substantial portion 25 of the area thereof, said plates being independently removable whereby to at will expose either one of the burners to the interior of the oven, while keeping the other excluded, in combination with a common fuel 30 supply for both burners and means compelling the ignition of both of the burners, so that they at all times perform the heating function whether or not one or the other of the radiating plates is removed.

35 2. In a combination fireless cooker and gas range, the combination of a substantially closed oven part surrounded by non-conducting walls, a horizontally disposed metallic partition having peripheral depending sup- 40 porting flanges, said plate being removable at will and forming in effect the top and sides of a burner chamber and the bottom of the oven, a plurality of disk-shaped radiating plates covering openings in said parti- 45 tion and constituting in effect a continuation of the top surface of said partition, said disk-shaped plates having implement receiv-

ing parts whereby the same may be independently removed at will, a burner disposed below each of said disk-shaped radiating plates and adapted to extend over a substantial area thereof, a single gas supply means for the burners, and an elongated conduit arranged in the chamber below the partition, establishing direct connection between the burners and having a series of outlet openings in its upper surface.

3. In a combination fireless cooker and gas range, the combination of a substantially closed oven having surrounding non-conducting walls and a bottom plate, a horizontally disposed metallic plate forming a partition and having depending peripheral flanges adapted to rest upon said bottom plate of the oven, the partition with said flanges forming a base for the oven, and an inclosing burner chamber between the partition and base plate, said partition having a plurality of detachable spaced removable annular heat radiating sections, a removable 70 disk-shaped radiating plate mounted upon each of said annular sections, the said disk-shaped plates and annular sections forming in effect a substantially continuous unbroken surface with said partition, a burner disposed below each of said disk-shaped plates whereby the flame therefrom will act upon substantially the entire area of said plates, a single gas supply means for the burners, an independent gas conduit establishing connection between the burners and having a series of openings in the upper surface thereof directed toward said partition, and said partition with said annular sections and disk shaped radiating plates being removable as a whole whereby the burners and the independent gas conduit may have direct communication with the interior of the oven.

In testimony whereof I hereunto affix my signature in the presence of two witnesses.

JOHN E. CHAMBERS.
